TRIGGER ACTUATED PORTABLE
SPRAY HEAD

Flora H. Ellinger, Chicago, Ill.

Application October 30, 1948, Serial No. 57,520

3 Claims. (Cl. 299—84)

1

The present invention relates generally to improvements in the art of spraying liquid for washing, rinsing and analogous purposes, and relates more particularly to improvements in the construction and operation of water spray and soap dispensing devices for dish washing and like purposes.

A primary object of my invention is to provide an improved trigger actuated portable spray head which is simple, compact and durable in construction, and which is moreover highly efficient in operation.

Numerous types of portable spray heads especially adapted for washing dishes, or the like, with a mixture of soap and water and for thereafter rinsing the washed articles with clear water have heretofore been proposed, and I am aware of the fact that some of these prior devices utilized liquid soap in the washing operation. Although a few of these prior spraying assemblages have proven quite satisfactory, considerable difficulty has been encountered in developing a spraying device wherein the soap is effectively mixed with the fresh water supply to produce a uniform and mild efficient washing mixture without undue and undesirable waste of soap. Furthermore, such prior spray washers have, for the most part, been rather bulky and cumbersome to manipulate, expensive to manufacture, and could not be quickly and easily converted from the fresh water spraying operation to the soap washing operation and vice versa. In addition, many of the prior sprays were not positive in action, and had many working parts which became stuck or otherwise out of working order.

It is therefore a more specific object of my present invention to provide an improved portable washing and rinsing spray device which obviates all of the above-mentioned disadvantages of prior spraying assemblages.

Another specific object of this invention is to provide an improved portable spray head which has a convenient upper gripping and manipulating handle, and wherein the soap supply valve is adapted to be manipulated by a trigger in a simple and convenient manner.

Another specific object of the invention is to provide an improved highly flexible and effective portable spray head which may be readily supplied with liquid soap without dismantling the unit or removing any parts therefrom, and wherein the liquid soap may positively be quickly fed to the washing zone in varying controlled amounts in an efficient and simple manner.

A further specific object of my present invention is to provide an improved trigger actuated portable spray head which is simple, compact and durable in construction, and which is moreover highly efficient in operation.

2

tion is to provide an improved trigger actuated portable spraying device wherein a supply of liquid soap is housed within a compartment entirely segregated from the fresh water supply chamber, and wherein varying quantities of the soap may be quickly fed to the washing zone in direct response to the action of the user's index finger.

Still another specific object of the present invention is to provide an improved portable spray washer and rinsing device adapted for connection with an ordinary faucet or other suitable source of liquid under pressure for dish-washing or like purposes, and capable of effectively performing washing operations in a quick and simple manner with a minimum amount of soap.

An additional specific object of the present invention is to provide an improved trigger actuated portable spray head composed of relatively few parts and adapted especially for use as a household kitchen appliance and which is extremely attractive and durable in construction and safe in operation.

Another additional object of the present invention is to provide an improved portable spray unit which is positive in action and flexible and efficient in use, which may be manufactured and sold at moderate cost, and in which all parts are readily accessible for inspection, replacement or repair.

These and other specific objects and advantages of the invention will be apparent from the following detailed description.

A clear conception of the several features constituting my present invention, and of the mode of constructing and of utilizing trigger actuated portable spray heads built in accordance with the improvement, may be had by referring to the drawing accompanying and forming a part of this specification, wherein like reference characters designate the same or similar parts in the several views.

Fig. 1 is a partial central vertical section through the improved spray washer, showing the trigger actuatable valve for delivering soap in normally closed position; and

Fig. 2 is a top view of the improved unit, parts being broken away to reveal normally concealed internal structure.

While the present invention has been shown and described herein as being applied to portable spray heads especially adapted for dish washing and rinsing purposes and wherein water under pressure is supplied thereto through a rubber hose attachable to a faucet, it is not my desire or in-

tent to thereby unnecessarily restrict the scope or utility of the improvement.

Referring to the drawing, the improved portable spray assemblage shown therein, comprises in general, a pair of oppositely-dished upper and lower members 5, 6, respectively, cooperating to form an approximately spherical main casing 7, the bottom wall of the lower dish-shaped member 6 being provided with a plurality of spaced spray openings 8 and with a transverse partition 9 dividing the main casing 7 into an upper soap-confining chamber 10 and a lower fresh water or spray chamber 11; a flexible tube 12 or the like adapted for attachment at one end to a faucet or other liquid supply source and attached at the other end to a nipple 13 or the like for communication with the interior of the lower spray chamber 11; a handle 14 having a base portion 15 secured to the upper casing member 5 and being formed with an upper gripping and manipulating portion 16; a bushing 17 or the like snugly confined within a central aperture 18 in the partition 9 and having the lower end thereof seated against the inner surface of the perforated wall of the lower casing member 6, the bushing 17 having a central vertical bore 19 extending therethrough and one or more angularly directed ports or passages 20 communicating at the upper ends thereof with the interior of the soap chamber 10 and terminating at their lower ends in the medial portion of the bore 19, the lower end of the bore 19 being in constant communication with the exterior through an aperture 21 formed in the bottom wall of the lower casing section 6; and a plunger or piston valve 22 snugly but slidably confined within the bore 19 of the bushing 17 for movement past the outlet ends of the ports 20 upon manipulation of a trigger 23 pivotally mounted as at 24 within a recess 25 of the handle 14 and connected to the plunger 22 by means of a link 26, connecting rod 27, link 28, lever 29 and link 30 as will be hereinafter more fully described.

To insure against leakage of soap from the upper chamber 10 to the lower chamber 11, the bushing 17 may be tightly screw-threaded into the aperture 18 of the partition 9, and the lower end of the bushing may be tightly seated against the lower wall of the casing member 6 by means of a screw 31, as shown, with the aperture or soap passage 21 being formed directly in the screw 31. Vertical swinging movement of the trigger 23 about its pivot 24 is imparted to the connecting rod or arm 27 through the link 26, and a bushing 32, snugly embracing the rod 27, is preferably provided in the upper casing member 5 to guide the rod 27 in its vertical reciprocating movement while preventing leakage of soap from the chamber 10. The lever 29 may be pivoted at one end as at 33 to the casing member 5 with the link 28 being attached to a medial portion of the lever 29 for transmitting motion thereto from the rod 27 and with the link 30 being attached to the swinging end of the lever 29 and to the upper end of the piston 22 for transmitting vertical reciprocating movement to this piston from the lever 29.

The piston valve 22 is normally maintained in a position such as shown in Fig. 1 with the ports 20 closed thereby so as to prevent escape of soap from the chamber 10 through the bore 19 and lower aperture 21, and this may be accomplished by means of a compression spring 34 embracing the rod 27 and coacting at one end with an inner shoulder on the casing member 5 and at the other end with the lever 29 to constantly urge the lever

29 and piston 22 downwardly. To maintain the spring 34 under slight compression and to form a positive stop for the trigger 23 in a position to enable finger actuation thereof, a pin 35 may be provided in the handle 14 spanning the recess 25.

The upper casing member 5 is provided with a top opening 36 to permit filling of the chamber 10 with liquid soap, and this opening 36 may be normally maintained closed by means of a plate 37 secured to the inner side of the dome of the member 5 by means of a screw or bolt 38, the plate 37 being adapted for snug seating engagement with the wall of the member 5 but being formed with an opening 39 adapted to register with the opening 36 of the casing upon rotation of the plate about the screw 38 with the aid of an actuating arm 40 or the like having an upper manipulating projection 43. To permit dismantling of the unit in the event of trouble, the handle 14 may be attached at its base 15 to the upper casing member 5 by means of bolts or screws 41, 42 or the like, and the casing members 5, 6 may be conveniently secured to each other as by means of screw threads. The various parts may be readily formed of available materials, and the handle 14 is preferably formed of heat-insulating material to insure utmost safety.

In operation, the chamber 10 of the device may be readily filled with a supply of liquid soap after 30 rotating the plate 37 about the pin 38 by means of the arm 40 until the aperture 39 is in alignment with the aperture 36. The plate 37 may thereafter be swung back to the position shown in the drawing, and with the parts in normal position as illustrated, there will obviously be 35 no leakage or feeding of soap from the chamber 10. After the free end of the hose 12 has been suitably connected to a faucet, not shown, or other source of liquid supply, the device may be 40 conveniently gripped and manipulated by means of the portion 16 of the handle 14; and clear liquid under pressure is conducted through the hose or tube 12, past the nipple 13, into the lower chamber 11 and then through the apertures 8 in the 45 lower casing wall in the form of a spray of clear liquid. If it is desired to supply soap to the spray, it is merely necessary to raise the trigger 23 about its pivot 24 by means of a finger, thereby lifting the rod 27 and swinging the lever 29 about its 50 pivot 33 to raise the piston valve 22 within the bore 19 of the bushing 17 while compressing the spring 34; and as the piston 22 is raised, the ports 20 are opened and a relatively small quantity of liquid soap is permitted to escape from 55 the chamber 10 through the ports 20 into the bore 19 below the plunger 22 and then through the aperture 21 to the washing or spraying zone where suds are created upon intermingling of the soap and spray. Upon release of pressure on the 60 trigger 23, the spring 34 will automatically return the plunger to normal position in an obvious manner whereby the ports 20 will again be closed at their lower extremities and the supply of liquid soap to the spraying zone will cease until the 65 trigger 23 is again actuated.

From the foregoing detailed description, it is apparent that my present invention provides an improved portable spray washer which is simple, compact and durable in construction, and which 70 is furthermore highly flexible and efficient in operation and exceedingly neat and attractive in appearance. The improved washing unit may be readily converted in a simple manner through the use of a finger, by actuation of the trigger 75 23, from a fresh water rinsing spray to a soapy

washing spray, and the device uses a minimum quantity of liquid soap with maximum efficiency. The gripping portion 16 of the insulating handle 14 provides for quick and effective manipulation in a simple and convenient manner; and since the gripping portion is remote from the casing 7 and is further spaced from the casing by the base portion 15 of the handle, the device may be manipulated with utmost safety even when operated with extremely hot liquid. In addition to returning the plunger valve 22 quickly and automatically to normally closed position, the spring 34 causes the plunger to force soap from the bore 19 through the opening 21 during downward movement, and provision of the stop pin 35 positively limits return movement of the trigger 23 and maintains the spring 34 under slight constant pressure to insure quick and positive action. Furthermore, it is apparent that the supply of liquid soap in the chamber 10 may be readily replenished in a simple manner by a novice without need for dismantling the device in any way; and if necessary the unit may be dismantled quickly and easily without the need of special equipment. It should also be noted that by forming the soap passage or bore 19 of the bushing 17 concentrically of the partition 9 and casing section 6 with the lever 29 pivoted on the wall of the casing section 5 remote from its connection with the valve 22, the casing sections 5, 6 may be readily rendered separable by means of screw threads or the like and the valve is moreover highly sensitive and responsive to the action of the eccentrically mounted actuating trigger 23. The device comprises relatively few parts, may be manufactured and sold at moderate cost, and has proven highly satisfactory in actual use.

It should be understood that it is not desired or intended to limit this invention to the exact details of construction, or to the precise mode of use, herein shown and described, for various modifications within the scope of the claims may occur to persons skilled in the art to which this invention pertains.

I claim:

1. A liquid and soap spraying device comprising, a universally movable casing having a central lower liquid soap delivery passage and an upper manipulating handle provided with a gripping portion spanning the axis of said passage, a soap confining chamber within said casing adjacent to the handle and having ports

communicating with the medial portion of said passage, a valve movable within said passage to control the delivery of soap through said ports, and a valve actuating trigger carried by said handle between said casing and said gripping portion.

2. A liquid and soap spraying device comprising, a universally movable casing having a central lower liquid soap delivery passage and an upper manipulating handle provided with a gripping portion spanning the axis of said passage, said handle being provided with a recess at one end of the gripping portion thereof, a soap confining chamber within said casing adjacent to the handle and having ports communicating with the medial portion of said passage, a valve movable within said passage to control the delivery of soap through said ports, a valve actuating trigger pivotally mounted in the recess of said handle and projecting therefrom between said casing and said gripping portion, and a stop cooperable with said trigger for limiting movement thereof while positively positioning said valve.

3. A liquid and soap spraying device comprising, a universally movable casing having a central lower liquid soap delivery passage and an upper manipulating handle provided with a gripping portion spanning the axis of said passage, a soap confining chamber within said casing adjacent to the handle and having ports communicating with the medial portion of said passage, a valve movable within said passage to control the delivery of soap through said ports, a valve actuating lever pivotally mounted within said chamber and connected to said valve, and a trigger carried by said handle between said casing and said gripping portion and operatively connected to a medial portion of said lever for actuating said lever.
